UNITED STATES PATENT OFFICE.

WILLIAM F. CLARK, OF SAN FRANCISCO, CALIFORNIA.

DESIGN FOR A LABEL.

SPECIFICATION forming part of Design No. 31,379, dated August 8, 1899.

Application filed April 10, 1899. Serial No. 712,547. Term of patent 14 years.

To all whom it may concern:

Be it known that I, WILLIAM F. CLARK, a citizen of the United States of America, residing in the city and county of San Francisco and State of California, have invented and produced a new and original Design for a Label, of which the following is a full, clear, and exact description, reference being had to the accompanying drawing, forming part thereof.

My design is intended as a label. In the accompanying drawing it is shown upon a rectangular plane.

As shown in the drawing, the leading or material features of my design consist of an oval-shaped field *a*, inclosed by a border of open scrollwork *b*, separating the field from the body or ground of the label and partially overlying the body. The field or space inclosed by this border contains an ideal coat of arms composed of two female figures seated side by side and occupying the lower central portion of the space. One of the figures *c* is represented with a liberty-cap on her head, an olive branch in her right hand and supported with her left hand in upright position turned to the front, a shield with a cross-bar of stars on a solid field, and below the bar thirteen perpendicular stripes. The other figure *d*, in seated position, wearing a Roman corselet and a helmet on her head, supports with the right hand a trident spear and an oval shield, bearing on its face the double

cross of St. George and St. Andrew. At the right of this figure a lion in crouched position, with the head turned to the front, fills the foreground at the left-hand side of the figure.

At the corresponding outer side of the opposite figure the representation of an eagle with one wing upraised and the head outstretched occupies the foreground, a horizontal line dividing the inclosed space into two parts on the longer axis of the oval and from the center thereof, between the two figures, a sunburst with extending rays spread over the field above that line.

Between the two figures, in the center of the oval field, are two flags *e f* with crossed staffs and a sphere or circle *g* described in the upper angle between them. One of the flags displays stars on a field in the upper corner and the thirteen stripes, and the other flag has the double cross in the upper corner corresponding with the oval shield below.

Having thus described my invention, what I claim as new, and desire to secure by Letters Patent, is—

The design for a label as herein shown and described.

In testimony that I claim the foregoing I have hereunto set my hand and seal.

WILLIAM F. CLARK. [L. S.]
